UNITED STATES PATENT OFFICE

147,547

DESIGN FOR A HANDBAG

Elizabeth N. Graham, New York, N. Y.

Application October 18, 1946, Serial No. 134,043

Term of patent 14 years

(Cl. D87—3)

To all whom it may concern:

Be it known that I, Elizabeth N. Graham, a citizen of the United States of America, residing in New York city, county of New York and State of New York, have invented a new, original, and ornamental Design for a Handbag, of which the following is a specification, reference being had to the accompanying drawing, forming part thereof, wherein,

The rear of the handbag is identical in appearance to the front shown in Figure 1.

I claim:

The ornamental design for a handbag, substantially as shown and described.

ELIZABETH N. GRAHAM.
